Primary Examiner — R. Johnson(74) *Attorney, Agent, or Firm* — Alix, Yale & Ristas, LLP(57) **CLAIM**

The ornamental design for the hook for strap for musical instrument, as shown and described.

DESCRIPTION

FIG. 1 is a front perspective view of a hook for strap for musical instrument showing my new design;

FIG. 2 is a first side elevation view thereof;

FIG. 3 is a second side elevation view thereof; showing the opposite side relative to FIG. 2;

FIG. 4 is a rear elevation view thereof;

FIG. 5 is a front elevation view thereof;

FIG. 6 is a bottom plan view thereof; and,

FIG. 7 is a top plan view thereof.

The broken lines in FIGS. 1-7 represent the portions of the hook for strap for musical instrument which form no part of the claimed design.
